United States Patent Office

Des. 233,185
Patented Oct. 8, 1974

233,185

INVERTIBLE SIGN

Elmer E. S. Lengyel, 4655 Wild Indigo 231,
Houston, Tex. 77027

Filed Apr. 3, 1972, Ser. No. 240,909

Term of patent 14 years

Int. Cl. D20—03; D18—03
U.S. Cl. D96—12 E

The figure is a view of an invertible sign showing my new design, the sign being shaded to indicate contrast.

I claim:

The ornamental design for an invertible sign, as shown and described.
